(57) **CLAIM**

The ornamental design for an electronic device, as shown and described.

DESCRIPTION

FIG. 1 is a top, front, and side isometric view of a first embodiment of an electronic device embodying the new design;

FIG. 2 is a bottom, back, and side isometric view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view along lines 9-9 in FIG. 7; and

FIG. 10 is a detail view of area 10 in FIG. 9.

FIG. 11 is a top, front, and side isometric view of a second embodiment of an electronic device embodying the new design;

FIG. 12 is a bottom, back, and side isometric view thereof;

FIG. 13 is a front view thereof;

FIG. 14 is a back view thereof;

FIG. 15 is a first side view thereof;

FIG. 16 is a second side view thereof;

FIG. 17 is a top view thereof;

FIG. 18 is a bottom view thereof;

FIG. 19 is a cross-sectional view along lines 19-19 in FIG. 17; and

FIG. 20 is a detail view of area 20 in FIG. 19.

The broken lines showing portions of the electronic device throughout the figures, as well as those indicating cross-sectional and enlarged views in FIGS. 7, 9, 10, 17, 19, and 20 and break lines in FIGS. 11-16 and 19-20, form no part of the claimed design.

The appearance of any portion of the second embodiment of the electronic device between the wavy broken lines forms no part of the claimed design. In FIGS. 9, 10, 19, and 20, the dash-dot broken lines depicted on interior features of the
